UNITED STATES PATENT OFFICE.

OTIS TIFFANY GREGG, OF HACKENSACK, NEW JERSEY, ASSIGNOR TO THE GREGG COMPANY, LIMITED, A CORPORATION OF NEW YORK.

LOCK-LID JOURNAL BOX.

Application filed August 23, 1921. Serial No. 494,515.

To all whom it may concern:

Be it known that I, OTIS TIFFANY GREGG, a citizen of the United States, residing at Hackensack, in the county of Bergen and State of New Jersey, have invented certain new and useful Improvements in Lock-Lid Journal Boxes (for which I have obtained patent in Cuba, No. 2,186, dated November 5, 1914, on application filed March 28, 1914); and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to journal boxes adapted particularly for car wheel axles, and has for its object to provide a simple and efficient construction for locking the lid so as to prevent access to the interior of the box for removal of the ordinary brasses and other parts contained therein except by a person having a proper key for unlocking the lid. The invention is illustrated in the accompanying drawing in which—

Figure 1 is a perspective of the box showing the lid closed and locked;

Figure 2 is a perspective view showing the lid unlocked and open.

In the drawing the numeral 1 designates a journal box which may be of any approved type in general construction and having a lid 2 for closing the opening 3 through which access is had to the interior of the box, the ordinary brasses and other parts contained therein not being illustrated as they do not constitute the present invention.

The front of the box above the opening 3 is formed with an upwardly extending bracket 4 for hinging the lid 2 thereto by a pivot bolt 5 passing through the bracket and ears 6 formed at opposite sides of the lid and bearing against the outside walls of the bracket. The lid may be provided with a spring 7, preferably in the form of a flat or leaf spring, adapted to bear against the cross

bar of the bracket, or other suitable part, so as to hold the lid in a raised position when open, although this spring may be omitted without departing from other features of the invention. For the purpose of locking the lid in its closed position there is formed as a part of the lid at one side a hollow boss 8 in which is seated a threaded bolt 9 the inner end of which, when the bolt is screwed up, will bear against the side wall of the box so as to securely lock the lid to the box. When screwed to locking position the outer end of the locking bolt lies wholly within the hollow boss so that a key of appropriate form must be inserted to engage the angular head of the bolt in order to turn the bolt to unlock the lid; and for greater security the space between the bolt head and the inner wall of the hollow boss is such that the bolt cannot be turned by inserting the fingers of the hand, and thus the use of a suitable tool for the purpose is necessary. It will be observed that the hollow or tubular boss is carried by the lid and fits outside the wall of the box when the lid is closed and also that the boss does not move with the bolt when the bolt is turned and that the bolt has its bearing directly in the boss and not in the side wall of the box, all of which advantages will be appreciated by the skilled in the art.

There is shown a flange 10 fitted to the inside of the lid which when the lid is closed will lie alongside the inner wall of the box but this can be omitted as it is not essential although desirable under some conditions to be used.

Having described my invention and set forth its merits what I claim is:

1. A lock-lid for journal boxes formed with a hollow boss to lie opposite the side of the box when the lid is closed, and a locking bolt threaded in said boss and adapted to be screwed up to bear against the side of the box and lock the lid in its closed position and have its head lie within the boss when in locked position.

2. A lock-lid for journal boxes formed with a boss carrying a locking bolt adapted

to bear against a part of the box to lock the lid closed, and a flange on the inside of the lid near the boss on the lid and adapted to lie alongside the inside wall of the box when the lid is closed.

3. A lock-lid for journal boxes formed with a boss carrying a locking bolt adapted to bear against a part of the box to lock the lid in a closed position, and a spring for

holding the lid in a raised position when opened.

In testimony whereof I affix my signature in presence of two witnesses.

OTIS TIFFANY GREGG.
